[57] CLAIM

The ornamental design for a buckle, as shown and described.

DESCRIPTION

FIG. 1 is a top plan view of a male member of a first embodiment of a buckle showing my design;
 FIG. 2 is a right side elevational view thereof;
 FIG. 3 is a front elevational view thereof with the rear view being a mirror image thereof;
 FIG. 4 is a left side elevational view thereof;
 FIG. 5 is a bottom plan view thereof;
 FIG. 6 is a top plan view of a female member of the first embodiment of a buckle showing my design;
 FIG. 7 is a left side elevational view thereof;
 FIG. 8 is a front elevational view thereof with the rear view being a mirror image thereof;
 FIG. 9 is a right side elevational view thereof;
 FIG. 10 is a bottom plan view thereof;
 FIG. 11 is a top plan view of the male member and female member of the first embodiment of the buckle assembled showing my design;
 FIG. 12 is a right side elevational view thereof;
 FIG. 13 is a front elevational view thereof with the rear view being a mirror image thereof;
 FIG. 14 is a bottom plan view thereof; and,
 FIG. 15 is a left side elevational view thereof.
